UNITED STATES PATENT OFFICE.

FRANK R. PACKHAM, OF SPRINGFIELD, OHIO, ASSIGNOR TO THE SUPERIOR DRILL COMPANY, OF SAME PLACE.

GRAIN-DRILL.

SPECIFICATION forming part of Letters Patent No. 429,320, dated June 3, 1890.

Application filed December 23, 1889. Serial No. 334,607. (No model.)

To all whom it may concern:

Be it known that I, FRANK R. PACKHAM, a citizen of the United States, residing at Springfield, in the county of Clark and State of Ohio, have invented certain new and useful Improvements in Grain-Drills, of which the following is a specification.

My invention relates to an improvement in grain-drills; and it especially relates to constructions particularly adapted for use in shoe-drills, though the constructions may be applied with equally good results to other forms of grain-drills.

The object of my invention is to provide novel means for supporting and operating the lifting and pressure mechanism for raising and lowering the shoes.

A further object of my invention is to provide a novel means for supporting a seat in a convenient position with reference to the lifting and pressure devices.

My invention consists in the various constructions and combinations of parts herein-after described, and set forth in the claims.

In the accompanying drawings, Figure 1 is a transverse sectional view, shown in elevation, of a machine embodying my invention. Fig. 2 is a plan view of the same, the hopper and some of the parts being removed to better illustrate the novel features of my invention. Fig. 3 is a detail view in perspective of the seat and its supporting mechanism. Fig. 4 is a detail view in perspective of a portion of the raising and lowering mechanism. Figs. 5 and 6 are detail views of some of the parts hereinafter referred to.

Like parts are indicated by similar letters of reference throughout the several views.

In the said drawings, A A represent the frame of a drill, which is supported at each end on suitable carrying-wheels B, from which motion is derived to operate the feeding mechanism in a well-known manner, these constructions being omitted in the drawings for perspicacity, as they form no part of the present invention.

C is the hopper, which is supported, as usual, at each end on the respective side rails a a of the main frame.

D D are the shoes, which are connected to

the main frame underneath the same in the usual way by drag-bars E. Each of the shoes is preferably provided with a pressing and covering wheel D', journaled in a suitable hanger D², pivoted to the shoe D, and provided with means for connecting the same rigidly to the shoe or permitting it to move independently therewith in a manner which has now become well known in the art. In order to secure the best results with this construction of shoe and presser-wheel, it is desirable that means be provided for raising and lowering the shoe or wheel independently, and it is desirable that the raising and lowering mechanism be arranged as near as possible over the pressing-wheel, so as to secure a direct lift or pressure thereon. In order to accomplish this without disarranging the other parts of the machine or interfering with the proper distribution of weight with reference to the pivotal center of the frame, I place the pressure and lifting mechanism at the rear of the hopper in the following manner: The side pieces a of the frame are extended backwardly beyond the hopper and the extended ends connected together by a tubular connection F. This tubular connection is preferably secured at each end in supporting-boxes b b, attached to the extended ends of the side pieces a a, although any other form of attaching device may be used.

The tubular connection F is preferably made of common black pipe or gas-pipe cut to a suitable length and inserted at each end in the supporting-boxes b b, and held firmly therein by set-screws b' b', or in any other well-known and suitable manner, the pipe being thus held firmly in position, and so forms a connection between the extended ends which adds rigidity to the frame and prevents the displacement of the extended ends of the side rails by spreading or otherwise. On the tubular connection F as thus constructed I support the lifting and pressure mechanism. This lifting and pressure mechanism consists, essentially, of a pressure-bar H, extending transversely across the frame A A, above the presser-wheels D', and parallel with the tubular connection F. Arranged along the press-

ure-bar H is a series of supporting-bearings c, each provided with a horizontal sleeve portion c' and a vertical sleeve c², formed integral and at right angles therewith. The horizontal sleeve portion c' fits the pressure-bar H, on which it is adapted to turn. The other sleeve portion c² is preferably constructed and prepared to fit over connecting-links d, which pass through said sleeve c² and are 5 pivotally connected at their lower ends d' to the hangers D² of the pressing-wheel D'. The connecting-links d are each provided with springs d², arranged on said links between an adjustable stop and the supporting-bearings, 10 substantially in the manner described in my former patent, No. 410,436, dated September 3, 1889, so that as the pressure-bar H is elevated or depressed the tension of the spring d² is varied so as to vary the pressure applied 15 to the wheel D' and the shoe D. An adjustable stop d³ is also provided above the bearing-support c to provide for lifting the wheel and shoe when the bearing-support comes in contact with said stop. To guard against lateral 20 movement of the sleeve c² on the connecting-link d, I form an increased bearing along the edge of the link d by providing an extension c³ at the top of the sleeve c². I also preferably cast the said sleeve on a chill to 25 prevent wear by its movement on the link d. By the use of the projection c³ an increased bearing is formed to guard against lateral movement of the sleeve without increasing the length of the link, the stop d³ being 30 adapted to pass the extended portion c³ and bear against the top of the sleeve proper c². 35

The pressure-bar H consists, preferably, of a straight round bar, each end of which is squared and tapered, as shown at e, and provided with a projecting screw-threaded portion e', as shown more clearly in Fig. 4. The squared and tapered portion e is adapted to fit in a similarly-constructed opening f in a rocking arm I, and is secured therein by nuts e², turned firmly on the screw-threaded portion e', thus drawing the arm I tightly onto the square tapered portion e.

The arms I are each provided in their opposite ends with an opening f', bored out or 50 otherwise prepared to fit on the tubular connection F, the bar H being preferably made of such length that the rocking arms I, when placed on the tubular connection F, stand alongside of and in close proximity to the 55 supporting-boxes b of said pipe-connection.

J is the lifting-lever, which is journaled at any convenient point on the tubular connection F. It is provided with an extended portion J', having a bearing g, preferably formed 60 open on the under side, as shown in Fig. 5, and adapted to embrace the pressure-bar H, a pin g', adapted to extend through the ends of the open bearing g, being provided to hold the bar H within said bearing.

K is a ratchet-stand, also fitted on the tubular connection F and placed in proximity to the lever J, and held in any desired position

by a set-screw h or in any other desired manner, the lever J being preferably arranged between said ratchet-stand and a collar h' and 70 provided with a suitable spring-bolt h², adapted to engage with the ratchet-stand K. The ratchet-stand K is preferably provided with an extended curved portion K', passing under the pressure-bar H and joined to the 75 hopper C, as shown in Fig. 1. By this construction it will be seen that by moving the lifting-lever J in either direction the shoes may be raised or lowered or pressure applied to the same, as desired. 80

By the construction of the ratchet-stand and lifting-lever, as described, the said ratchet-stand and lifting-lever may be placed in any desired position along the tubular connection F, and pivotally connected to the pressure- 85 bar H to operate the same.

By using the independent rocking arms I and providing a separate and independent connection between the lifting-lever J and the pressure-bar the pressure-bar is adapted 90 to be moved on its pivotal bearings more uniformly than when applied to one of the rocking arms at one end only of the pressure-bar, in which case the torsion of the rod is largely depended upon for raising or lowering the 95 opposite end of the pressure-bar.

On the tubular connection F, preferably in close proximity to the lifting-lever J, I place a hanger L. This hanger is formed, preferably, of a single piece of round iron or steel, 100 formed, as shown in Fig. 6, with two eyes k and a connecting loop k'. The eyes k fit snugly on the tubular connection F, allowing the loop k' to depend underneath the same. Extending through the loop k' is a tubular seat-support 105 M, formed, preferably, of a piece of black pipe or gas-pipe, which is reduced or flattened at its inner end to receive a bolt l, by means of which it is secured to a fastening-clip l', secured to a cross-bar a' of the main frame. 110 This fastening-clip l' is provided with a series of openings l'', by means of which the position of the support M may be varied as desired by changing the location of the bolt l in the respective openings. The seat M' is 115

adapted to be supported on the seat-support M by providing a saddle l³, to fit over the seat-support M, the seat M' being preferably secured in proper position by a bolt l³, which passes through the seat-support M, 120 a series of openings l'' being provided in said seat-support to furnish means for adjusting the position of the seat forward or back on the said seat-support. I also preferably provide on the seat-support M 125 a foot-rest N, which consists, preferably, of a U-shaped strap m, extending over a collar m', formed in the nature of a saddle adapted to be secured in different positions on the seat-support M by a set-screw m², or in any other well-known or equivalent manner. Attached to the U-shaped bar m are the foot-supporting pieces m³, preferably made separate from the bar m and adapted 130

to be secured thereto in different positions by means of a series of openings m^5 , by means of which the foot-supporting pieces may be raised or lowered with reference to the seat-
5 support M. It will be seen that by this construction I provide a seat and seat-support which may be readily adjusted to any desired position with reference to the lifting-lever and mechanism, the constructions being
10 such that the seat may be readily removed and replaced, as desired.

The parts of the lifting mechanism and the seat-support are all so arranged as to be readily adjustable to all sizes of machines or
15 for operating under different conditions. The support F and the seat-support M being tubular, as described, a very rigid construction is secured with very little weight of material, the construction being at once simple
20 and compact and adapted to be easily and readily removable and adjusted to position.

If desired, one or more rocking arms I may be journaled on the supporting-pipe F and attached to the pressure-bar H. In large machines, where a considerable number of shoes
25 are employed, I preferably form the lifting-bar H with two or more parts and provide a lifting-lever for each part. When formed in two parts, the lifting-levers for the respective
30 parts may be placed at each side of the seat-support and in convenient reach of the operator from the seat. Where a very small number of shoes are used the lifting-lever may be attached at one end directly to one of
35 the rocking arms I, in which case the ratchet-stand K may be formed with one of the supporting-boxes b and secured directly to the main frame, as shown in Fig. 5.

It will be seen that all of the above-described constructions are adapted for either large or small machines, the constructions being at the same time so simple that very little machine-work is required to complete the same.

Having thus described my invention, I claim—

1. In a grain-drill, the combination, with the main frame having the extended ends, of a tubular support connecting said ends and secured stationary thereto, a pressure-bar forming a part of the raising and lowering mechanism, rocking arms connected rigidly to said pressure-bar, said rocking arms being journaled on said tubular support $x x$, and a lifting-lever journaled on said tubular support $x x$ and connected to said pressure-bar, substantially as specified.

2. The combination, in a grain-drill, with the main frame and shoes, of a pressure-bar arranged above said shoes, said pressure-bar being provided with rocking arms journaled on a transverse pipe or bar connected at each end rigidly to the rear ends of said frame, connections from said shoes to said pressure-bar, a lifting-lever on said pipe or bar and connected to said pressure-bar, and a ratchet-stand secured to said pipe or bar and adapted

to be engaged by said lifting-lever and hold said pressure-bar in different positions of adjustment, substantially as specified.

3. The combination, in a grain-drill, with a frame having extended ends, of a tubular connection supported in bearings secured to the extended ends of said frame, means for rigidly securing said tubular connection in said bearings, a pressure-bar supported parallel to said tubular connection by rocking arms adapted to oscillate on said tubular connections, pivoted connections from said pressure-bar to the shoes, and means for moving said pressure-bar about said tubular connection, substantially as specified.

4. The combination, in a grain-drill and with the shoes thereof, of a pressure-bar arranged above said shoes having square ends to fit into similarly-shaped openings in rocking arms which are journaled on a tubular bar extending transversely across said frame, a lifting-lever also journaled on said tubular bar, and a connection between said lifting-lever and pressure-bar, substantially as specified.

5. The combination, with the frame having the extended ends, of a hollow pipe or rod having supporting-boxes on the extended ends of said frame, means for securing said pipe or rod against movement through said boxes, and a seat-support connected to said frame and suspended from said pipe or rod, substantially as specified.

6. The combination, in a grain-drill, with a main frame and shoes, of a raising and lowering mechanism for operating said shoes, said raising and lowering mechanism being entirely supported on a stationary transverse tubular bar connecting the extended ends of said frame, substantially as specified.

7. The combination, with the main frame and hopper of a grain-drill, of a pressure-bar having rocking arms journaled on a transverse tubular bar connecting the ends of said frame, a ratchet-stand, and lifting-lever journaled on said tubular bar, said lifting-lever being pivotally connected to said pressure-bar and said ratchet-stand being provided with an extended portion connected to said hopper, substantially as specified.

8. The combination, with a pivoted and suspended seat-support and an adjustable seat thereon, of a foot-support adjustably secured on said seat-support and provided with extensible foot-rests, substantially as specified.

9. The combination, with a transverse bar and a suspended seat-support, of a suspending loop formed of a single piece of substantially uniform size with eyes to fit said transverse pipe, and a loop to receive said seat-support, substantially as specified.

10. The combination, with a grain-drill frame having a transverse bar a' , of a transverse hollow pipe or rod parallel with said bar and connecting the rear extended ends of said frame, a hollow seat-support suspended from said transverse pipe, said seat-support

being connected to said transverse bar by a fastening-clip, and means for adjusting the end of said seat-support with reference to said fastening-clip, substantially as specified.

5 11. The combination, with a transverse tubular support, of a tubular seat-support supported therefrom, a seat supported on a saddle adapted to fit said tubular support, a fastening-bolt extending through said seat and saddle, and a series of openings in said seat-support adapted to receive said fastening-bolt, substantially as specified.

12. The combination, with the main frame and shoes connected thereto, of a pressure-bar arranged above and connected to said shoes, a lifting-lever, and ratchet-stand supported on a transverse tubular bar, on which said pressure-bar is also pivoted, said lifting-lever being provided with an extended arm 20 formed with an open bearing adapted to receive said pressure-bar, whereby said lifting-lever may be connected to or disconnected from said pressure-bar and adjusted to different positions in the length thereof, substantially as specified.

13. The combination, with the frame and shoes, of a pressure-bar connected to said

shoes, said pressure-bar being provided with rocking arms journaled on a transverse pipe or rod supported on said frame, a lifting-lever, 30 and ratchet-stand supported on said transverse pipe or rod, said lifting-lever being adjustably connected to said pressure-bar, substantially as specified.

14. The combination, with the shoes and a pressure-bar arranged above the same, of the bearing-supports, each journaled on the said pressure-bar and provided with a sleeve c^2 , having an extended portion c^3 , substantially as and for the purpose specified.

15. The combination, with a shoe, the pressure-bar, and a connecting-link between the same, of a bearing-support having horizontal and vertical sleeves for the pressure-bar and link, respectively, the vertical sleeve being 45 provided with an extended bearing on said link, substantially as specified.

In testimony whereof I have hereunto set my hand this 18th day of December, A.D. 1889.

FRANK R. PACKHAM.
